WHOLE No. 1,399.

Stoves.

WALTER W. STANARD, OF BUFFALO, NEW YORK,

ASSIGNOR TO JEWETT & ROOT, OF SAME PLACE.

Letters Patent for a Design No. 34, dated April 9, 1861.

SPECIFICATION.

TO ALL WHOM IT MAY CONCERN:

Be it known, that I, WALTER W. STANARD, of the city of Buffalo, county of Erie and State of New York, (assignor to Jewett & Root, of the same place,) have invented or produced a certain new and original design for Coal Stoves, which I denominate by the name of "Meridian;" and I do hereby declare that the following is a full and exact description of the same, reference being had to the accompanying photographic plates, and the letters of reference marked thereon, in which—

Fig. I represents the bottom plate.

" II represents the bottom top plate.

" III represents the top plate and cover.

" IV represents the door frame and door.

The bottom plate, fig. I, is surrounded by a border of denticulations *a* at the sides and back, carved scrolls and leaves *b* at the front, and scrolls and leaves *c*, connecting the denticulations at the back with those at the sides.

The bottom top plate, fig. II, is circular in form, with an extension at the back for the smoke pipe.

It is surrounded by a denticulated moulding *d*, with scalloped edges and carved work *e*, upon the smoke pipe extension.

In the top plate and cover, fig. III, the top plate is surrounded by a border of denticulations *g*.

Stanard's Design for Stoves.

The cover consists of the open ornamental scroll work *h*, with an "ogee" border or rim, with openings *i* at regular intervals, and an ornamental scroll handle *j* at the centre, as represented in the plate.

In figure IV, representing the door frame and door, the door frame is surrounded by an ornamental border of scrolls and leaves *k*. The door opening is surrounded by an embossed or carved border or moulding *l*.

The door is ornamented by a beaded moulding *m*, with small carved ornaments at the corners, the configuration and arrangement of all the several parts being distinctly represented in the plate.

I claim the ornamental design for a coal stove, herein described and represented in each of the accompanying photographic plates, figs. I, II, III, IV..

WALTER W. STANARD.
